UNITED STATES PATENT OFFICE.

CASPER FAUST, OF OSHKOSH, WISCONSIN.

BOLSTER-STAKE HOLDER.

1,082,074.

Specification of Letters Patent. Patented Dec. 23, 1913.

Application filed October 9, 1913. Serial No. 794,192.

To all whom it may concern:

Be it known that I, CASPER FAUST, a citizen of the United States, and resident of Oshkosh, in the county of Winnebago and State of Wisconsin, have invented certain new and useful Improvements in Bolster-Stake Holders; and I do hereby declare that the following is a full, clear, and exact description thereof.

10 The object of my invention is to provide a simple, economical and effective releasable bolster-stake holder for attachment to flat cars or the like, the same being an improvement of that general type of stake 15 holders for which an application for patent was filed by me April 11, 1913, Serial No. 760,456.

With the above object in view the invention consists in certain structural elements 20 and combination of parts as hereinafter set forth with reference to the accompanying drawings and subsequently claimed.

In the drawings Figure 1 represents a side elevation of a bolster stake holder embodying 25 the features of my invention, the same being shown attached to the side sill of a car, with parts broken away and in section to more clearly illustrate details of construction; Fig. 2, a sectional view of the same, 30 the section being indicated by line $x-x$ of Fig. 1; Fig. 3, a similar sectional plan view of the bolster stake holder showing means for attaching it to a bolster block, which block is arranged transversely of the car 35 floor and adapted to serve as a seat for the load of logs or analogous freight, and Fig. 4, a sectional plan view of another form of my invention, wherein the cheek-pieces forming the movable jaws are each hinged.

40 Referring by characters to the drawings, 25 represents the side sill of a car-frame having bolted thereto a bracket, which bracket is provided with a base-plate 26 and an integral jaw member 27 that is curved at 45 its end to partially form the mouth portion of a stake socket. The stake socket is completed by a similarly curved cheek-piece 28, which cheek-piece is provided with an apertured shank ear 28' that is nested between 50 apertured knuckles 26' that form part of the bracket. The knuckle-joint between the movable cheek-piece and the bracket is completed by a pintle-bolt 29, which pintle-bolt passes through the apertures of the bracket 55 knuckles and ear 28' of the said cheek-piece. Attention is called to the fact that the mov-

able or hinged cheek-piece 28 is of less width than the rigid cheek-piece 27, whereby the said movable cheek-piece is protected, due to the fact that the logs, when discharged from the side of the car will roll over the high face of the fixed cheek-piece 27. It is also apparent that the stake-holder elements just described can be reversed for either right or left hand stake sockets. 60

Extending from the fixed cheek-piece 27 is an apertured cleat 30, there being a corresponding apertured cleat 31 extending from the hinged cheek-piece 28. The cleat 30 is adapted to receive one end link 32 of a 70 chain section, the opposite end link 33 of which is fitted over the cleat 31 and detachably secured thereto by means of a key-pin 34. The end link 32 of the chain section is permanently secured to the cleat 30 of the 75 fixed cheek-piece by means of a cotter-pin 30'. Extending from the detachable end link 33 is a stripper-pin 35, which stripper-pin is adapted to be engaged by a rod, chain or lariat, whereby the link is removed from 80 the cleat after the key-pin has been extracted.

As shown in Figs. 1 and 2, the movable cheek-piece is closed and locked by the chain section to form a socket for the stake A' and 85 when it is desired to remove said stake the key-pin, as previously stated, is extracted and thereafter the detachable end link 33 removed from the cleat, whereby pressure of the stake will cause the jaw member 28 to 90 swing open, permitting the stake to drop from its seat in order to release the load.

Fig. 3 illustrates the stake-holder similar in construction to that previously described with the exception that the base-plate 26 is 95 provided with rearwardly extended flanges 26'' which form a socket for a transversely disposed bolster block 36, the same being secured to the bracket flanges by suitable bolts, as shown. The device previously described is adapted to be tripped from the same side of the car to which it is applied, while that form of device shown in Fig. 3 is designed to be tripped from the opposite side of the car. With this in view the releasable end link 33 is provided with a vertically extended stripper-pin 35', which stripper-pin is engaged by an auxiliary link 36 of a trip chain or cable 37, the said end link 36 of the trip-chain being also fitted 100 over the cleat 31', whereby the key-pin 34' serves to hold both links in place. It is ap-

parent from the foregoing description that when it is desired to trip the stake A' in this instance after the key-pin has been removed that the operator, standing upon the opposite side of the car, can manipulate the release chain 37, whereby its end link 36, together with the end link 33 of the chain section which connects the cheek-pieces is released from the cleat, thus permitting the hinged jaw 28 to swing open, whereby the stake will fall from its socket.

Fig. 4 illustrates still another form of my invention, wherein the base-plate 26 is provided with oppositely disposed sets of knuckles, between each of which sets is hinged a swinging cheek-piece 38, 38. These cheek-pieces carry apertured cleats 39, 39, and one of the cleats has permanently secured thereto the end link of a chain stretch 40, the said end link being locked by a cotter-pin 41. The opposite end of the chain stretch is provided with a releasable link 41', which link is temporarily secured to the juxtaposed cleat 39 by a key-pin 42, the said end link 41' being provided with a stripper-pin 43. The chain section constituting means for locking the hinged cheek-pieces together is manipulated in a manner similar to that previously described in connection with the other forms of my invention shown, it being apparent that when said cheek-pieces are freed that they will swing open to permit the stake A' that is socketed therein to fall from its seat, whereby the load will be deposited at the side of the car corresponding to the released stakes.

I claim:

1. A stake holder comprising a bracket having a base-plate provided with cheek-pieces extending therefrom, at least one of the cheek-pieces being in hinge connection with the base-plate to form a stake-socket, cleats extending from the cheek-pieces, a chain section permanently secured to one of the cleats and provided with an end link for engagement with the opposite cleat, means for detachably securing said end link to the cleat, and a stripper means in connection with said end link.

2. A stake holder comprising a bracket 50 having a base-plate and a fixed cheek-piece extending therefrom, a corresponding cheek-piece in hinge connection with the base-plate adapted to articulate with the fixed cheek-piece, an apertured cleat extending from 55 each cheek-piece, a locking chain for the cheek-pieces having an end link permanently secured to one of the cleats, means for detachably securing the opposite end link of the locking chain section to the other cleat, 60 and a stripper-pin carried by the detachable end link.

3. A stake-holder comprising a bracket having a base-plate and a fixed cheek-piece extending therefrom, apertured knuckles 65 extending from the base-plate, a cheek-piece having an apertured ear for nested engagement with the knuckles, a pintle connecting the cheek-piece, ear and knuckles, a cleat extending from the fixed cheek-piece, a similar 70 cleat extending from the movable cheek-piece, a locking chain section having an end link permanently secured to one of the cheek-pieces, means for temporarily securing the opposite end link to the other cleat, 75 and stripper means in connection with the temporarily secured end link.

4. A stake-holder comprising a bracket having a base-plate and a fixed cheek-piece extending therefrom, a corresponding cheek-piece in hinge connection with the base-plate, the same being of less width than the fixed cheek-piece, a cleat extending from 80 each cheek-piece, a chain section permanently secured to one of the cleats, means 85 for temporarily securing the opposite end of the chain section to the other cleat, and means in connection with the chain section for stripping the same from that cleat to which it is temporarily secured.

In testimony that I claim the foregoing I have hereunto set my hand at Milwaukee in the county of Milwaukee and State of Wisconsin in the presence of two witnesses.

CASPER FAUST.
